US00D745877S

(12) **United States Design Patent**
Supino et al.

(10) **Patent No.:** US D745,877 S
(45) **Date of Patent:** ** Dec. 22, 2015

(54) **DISPLAY SCREEN WITH GRAPHICAL USER INTERFACE**

(71) Applicant: **Microsoft Corporation**, Redmond, WA (US)

(72) Inventors: **Dina-Marie LeDonne Supino**, Redmond, WA (US); **Stephen Danton**, Seattle, WA (US); **Jonathan Harris**, Redmond, WA (US); **Jonah Sterling**, Redmond, WA (US); **Jon Lee**, Seattle, WA (US); **Jesse Francisco**, Redmond, WA (US); **William Staples**, Redmond, WA (US); **Karanddeep Anand**, Redmond, WA (US); **Kristofer J. Owens**, Redmond, WA (US)

(73) Assignee: **Microsoft Corporation**, Redmond, WA (US)

(**) Term: **14 Years**

(21) Appl. No.: **29/470,129**

(22) Filed: **Oct. 17, 2013**

(51) **LOC (10) Cl.** 14-04

(52) **U.S. Cl.**

USPC **D14/485**

(57) **CLAIM**

The ornamental design for a display screen with graphical user interface, as shown and described.

DESCRIPTION

The FIGURE is a front view of a display screen with graphical user interface showing my/our new design.

The broken line showing of the text, the numerals, the icons, the remainder of the user interface and the remainder of the display screen is for environmental purposes only and forms no part of the claimed design.

1 Claim, 1 Drawing Sheet
